(57) **CLAIM**

We claim the ornamental design for an air curtain merchandiser with curved front, as shown and described.

DESCRIPTION

FIG. 1 is a perspective view of a merchandiser showing my new design;
FIG. 2 is a front elevational view of FIG. 1;
FIG. 3 is a top view of FIG. 1;
FIG. 4 is a left side elevational view of FIG. 1;
FIG. 5 is a right side elevational view of FIG. 1;
FIG. 6 is a rear elevational view of FIG. 1; and,
FIG. 7 is a bottom plan view of FIG. 1.
